HANDLE FOR PORTABLE SPRAY CLEANING NOZZLES OR THE LIKE

Charles W. Titus, Wake County, N.C., assignor to Watson
Seafood and Poultry Co., Inc., Raleigh, N.C.

Filed June 3, 1966, Ser. No. 2,535

Term of patent 14 years

(Cl. D91—1)

FIG. 1

FIG. 2

FIG. 1 is a perspective view of a handle for portable spray cleaning nozzles or the like, showing my new design; and

FIG. 2 is a front elevational view of the same.

The connected hose shown in broken lines in FIG. 1 is included for illustrative purposes only.

What is claimed is:

The ornamental design for a handle for portable spray cleaning nozzles or the like, as shown and described.
